WALL AND CEILING BOARD SPLICE

Filed Feb. 7, 1928

FIG. 2

INVENTOR.

Calvin Campbell

BY

G. J. Salamone
ATTORNEY.

UNITED STATES PATENT OFFICE.

CALVIN CAMPBELL, OF DENVER, COLORADO, ASSIGNOR TO THE COLORADO FUEL AND IRON COMPANY, OF DENVER, COLORADO, A CORPORATION OF COLORADO.

WALL AND CEILING BOARD SPLICE.

Application filed February 7, 1928. Serial No. 252,533.

This invention relates to splice-clips for faces and alternately in opposite directions, thereby securing the boards against relative lateral displacement. 55
This invention relates to splice-clips for faces and alternately in opposite directions, thereby securing the boards against relative lateral displacement. 55
5 The principal object is to provide a clip of bendable sheet-metal which by a simple manipulation may be applied to firmly and securely fasten edge-to-edge adjacent wall- or ceiling-boards in permanent alinement and against 10 relative displacement.

Other objects of the invention reside in details of construction as will be clearly described in the course of the following description, with reference to the accompanying 15 drawings.

In the drawings, in the several views of which like parts are similarly designated,

Figure 1 represents a perspective view of 20 the splice-clip; Figure 2, a partially broken face-view of two adjoining wall- or ceiling-boards fastened together by one of the clips; and

Figure 3, a section taken on the line 3—3, Figure 2.

25 The splice-clip as shown in Figure 1, is made of a single preferably rectangular piece 5 of sheet-metal scored at its opposite longitudinal edges by parallel relatively transverse slits 6 and 7 for the formation of two 30 series of tongues 8 and 9.

The tongues 8 at one edge of the piece are bent at right angles to the body portion of the same, alternately in opposite directions, and the tongues 9 at the opposite edge of the 35 piece are defined by transverse bending lines 10 at the ends of the dividing slits 7.

The bending lines may or may not be used. If they are they may be formed by rows of 40 perforations as shown in the drawings, or by otherwise weakening the metal of which the clip is made.

45 Figures 2 and 3 illustrate the method of applying the clip to two pieces of wall- or ceiling-board 12 adjoining one another in a common plane.

The body of the clip is inserted between the adjoining edges of the boards, preferably from their sides opposite to their finished surfaces, until their tongues 8 engage the 50 sides of the boards.

The tongues 9 projecting at right angles to the finished surfaces of the board are now bent along their bending lines upon said sur-

faces and alternately in opposite directions, thereby securing the boards against relative lateral displacement. 55
After the tongues have been bent, they are forcibly driven into the surfaces of the boards with a hammer or other suitable means. This draws the boards tightly against the 60 tongues 8 on the opposite sides of the boards and thereby fastens the boards in place.

In order to obtain this result, the distance between the bending lines and the edge of the body-member of the clip at which the 65 angularly bent tongues 8 are formed, is slightly less than the average thickness of wall- or ceiling-boards, and by pressing the tongues 9 into the material of the boards, flush with the finished surfaces of the same, the clips 70 may be completely concealed by the fillers of filling strips or other material commonly used in surfacing or finishing walls and ceilings.

It will be apparent that the splice-pieces 75 formed and applied as shown and described, provide a normally invisible means to rigidly secure adjoining pieces of wall- or ceiling-board in perfect alinement by an extremely simple operation and at a very small expense 80 of material.

The splice-clip may be made of any bendable metal and coated with a rust-proof substance, if so desired, and minor details of construction may be resorted to within the 85 scope of the invention.

Having thus described my invention what I claim and desire to secure by Letters Patent is:

1. A splice-clip for wall- and ceiling-boards comprising a metal piece having at an edge thereof tongues bent at an angle and in opposite directions, and having at its opposite edge bendable tongues formed by transverse slits and weakened bending lines 95 adjacent the ends thereof.

2. A splice-clip for wall- and ceiling-boards comprising a metal piece having at opposite edges, bendable tongues formed by slits transverse to said edges, the tongues at one of the edges being further defined by weakened bending lines adjacent the ends of the slits.

In testimony whereof I have affixed my signature.

CALVIN CAMPBELL.
